COMBINED HAT AND SHOPPING BAG

Elberta Roy Woodside, Chicago, Ill.

Application April 20, 1934, Serial No. 721,444

3 Claims. (Cl. 2—175)

This invention relates to improvements in combined hat and shopping bag, and one of the objects of the same is to provide an improved hat having a freely removable crown, which latter, when removed from the brim will serve the purpose of a shopping bag. At the same time the remaining portion of the hat may be worn as a crownless hat, means being provided, if desired, for securing the hat upon the head against accidental displacement.

A further object is to provide an improved article of this character in which the detachable crown may be worn by itself, independently of the brim, or employed, as a shopping bag.

15 A further object is to provide improved means for detachably securing the crown and brim of the hat together.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which

25 Figure 1 is a perspective view of a hat of this character constructed in accordance with the principles of this invention.

Figure 2 is a view similar to Figure 1, showing the crown removed.

30 Figure 3 is a detail view in elevation, on an enlarged scale, showing the detachable crown and the bag formation.

Figure 4 is a top plan view, partly broken away and on an enlarged scale, of one form of the invention.

35 Referring more particularly to the drawing and to the form of the invention shown in Figures 1 to 4, the numeral 10 designates an annular hat brim member constructed of any suitable material, but preferably a sheet of flexible material such as fabric and the same may, if desired, be reinforced and maintained in shape by a rim member 11 constructed of any suitable pliable material housed within the brim.

40 This brim member is provided with an opening for the head, and which opening may be of any desired size and encompassing the opening is a flange member preferably in the form of an upright wall of appreciable extent, so as to impart a certain amount of rigidity or stiffness to the portion of the hat brim which encompasses the head.

45 Secured to the wall of the opening, preferably to the upright portion 12 and arranged so as to

cross each other, are flexible strips or members 13, any number of which may be provided but are preferably arranged in the form of a cross, and if desired, these strips may be secured together at their crossing point as indicated at 14.

5 The strips are of a length substantially greater than the diameter of the opening in the brim and constitute the sole means of support for the brim upon the head. If desired flexible members or tapes 15 may be secured to the brim so as to pass beneath the chin of the wearer to hold the hat brim against accidental displacement.

10 The numeral 16 designates generally a crown member which is of any desired configuration and is constructed of any suitable flexible material, such as fabric and the like, and the crown member is preferably formed of two pieces of material 17—18, each of which may be provided with a binding 19—20 around the edges thereof.

15 The two elements 17—18 are superposed and are secured together along their edges in any desired or suitable manner, such as by means of stitching 21, and portions of the elements are separate from each other so as to provide flaps on each side of the entrance opening between the elements 17 and 18 so as to form a bag or receptacle.

20 Separable fastening members 22—23, any number of which may be provided, are arranged along the edges of the flaps so as to constitute closures for securing the bag in a closed position.

25 The numeral 24 designates a handle, which may be formed of any suitable flexible material and the ends of the handle are secured as at 25 to one of the elements 17—18, and by means of which handle the bag or receptacle may be transported.

30 When the element 16 is employed as a crown for the hat, the handle 24 is inserted into the bag between the elements 17 and 18 through the open portion thereof, after which the flaps 17—18 are secured in a closed position by means of the fasteners 22—23.

35 Secured also to the crown member are additional fastening elements 26, any number of which may be provided, and which fastening elements 26 co-operate with fastening elements 27 that are secured to the brim member 10 so that when the crown member is placed in position upon the brim member the fastening elements 26 and one 40 of the fastening elements 23 will engage and co-operate with the fastening elements 27 on the brim member 10 for detachably securing the crown member 16 to the brim. The crown member when in position will pass over and rest upon 45

the flexible members 13 when the hat is on the head of the wearer.

With this construction it will be manifest that when it is desired to wear the article as a hat 5 with a crown, the crown member 16 is secured to the brim member in the manner just described, and the parts will appear as shown in Figure 1.

When, however, it is desired to employ a crown-less hat, the crown may be detached and the brim member then may be worn as a head covering, as shown in Figure 2. The crown may also be employed as a bag or receptacle when employed in the manner shown in Figure 3.

It will thus be manifest that the parts will be 15 firmly secured together in this manner, and the crown may be employed as a head covering, and the brim member may also be worn as a head covering, each independently with respect to the other or, if desired, the crown may be secured to 20 the brim to form a complete hat.

Obviously, any suitable or desired material may be employed, and the material may be of a waterproof nature and of a character that the device will be light in weight.

25 While the preferred forms of the invention have been herein shown and described, it is to be understood that various changes may be made in the details of construction and in the combination and arrangement of the several parts, within 30 the scope of the claims, without departing from the spirit of this invention.

What is claimed as new is:—

1. An article of the character described comprising a brim member having a head opening 35 therethrough, one or more flexible straps of a length greater than the diameter of the opening

and having portions thereof secured to the brim member, said straps extending across said opening whereby the brim member will be supported, when in use, entirely by the strap members engaging and resting upon the head of the wearer, a normally substantially flat crown member extending across the said head opening and resting upon said straps, and means for detachably securing the edge of said crown member to said brim, at points intermediate but spaced from the edges 10 of the brim.

2. A combined hat and shopping bag comprising a brim member having a head opening therethrough, means other than the edge of said opening for supporting the brim upon the head, a 15 separate and normally substantially flat bag constructed of flexible material and having an entrance opening between its walls, said bag being adapted to extend substantially flat across the said opening in the brim so as to rest upon the 20 said means to constitute a crown for the hat and to form a closure for the said head opening, and means for detachably securing the edge of the bag to the brim member at points intermediate but spaced from the edges of the brim. 25

3. An article of the character described comprising a brim member having a head opening therethrough, supporting means for the brim extending across said opening, a normally substantially flat crown member extending across the 30 said opening and resting upon the said supporting means, and means for detachably securing the edge of the said crown member to said brim at points intermediate but spaced from the edges of the brim. 35

ELBERTA ROY WOODSIDE.
